UNITED STATES PATENT OFFICE.

HENRY F. BECHMAN, OF BATTLE CREEK, MICHIGAN, ASSIGNOR TO DUPLEX PRINTING PRESS COMPANY, OF BATTLE CREEK, MICHIGAN, A CORPORATION OF MICHIGAN.

MEANS FOR AUTOMATICALLY CIRCULATING COOLING-WATER IN PLATE-CASTING BOXES.

1,250,772.

Specification of Letters Patent. Patented Dec. 18, 1917.

Application filed January 4, 1915. Serial No. 448.

To all whom it may concern:

Be it known that I, HENRY F. BECHMAN, a citizen of the United States, residing at Battle Creek, in the county of Calhoun and State of Michigan, have invented certain new and useful Improvements in Means for Automatically Circulating Cooling-Water in Plate-Casting Boxes; and I hereby declare that the following is a full, clear, and exact 10 description thereof, reference being had to the accompanying drawings, which form part of this specification.

This invention relates to stereotype plate casting boxes, and its object is to provide 15 means for maintaining the parts of the casting box at a temperature most suitable for plate casting while preventing overheating thereof, and this is allowed by novel means for automatically circulating water, or other 20 suitable cooling medium, through the portions of the casting box subjected to the most intense heat, so that such parts will be protected from injury and the box maintained at a substantially uniform temperature 25 which will enable plates to be cast more uniformly and with greater rapidity than has been heretofore practical with casting boxes of the same general type but to which the invention has not been applied. The 30 invention increases the efficiency of the box and obviates much of the trouble which has been heretofore experienced in attempting to keep such boxes at the best temperature for working.

The invention is particularly designed for use in connection with stereotype casting boxes of the type shown in my Patent No. 945,678, of January 4, 1910, and application Serial No. 866,295, filed October 12, 1914, 35 which latter covers the construction of the box illustrated in Figures 1 to 4 of the drawings; but the invention is applicable to semi-cylindrical plate casting boxes such as shown for example, in my Patent No. 853,752, of 40 May 14, 1907. I will explain the invention as applied to such boxes.

In said drawings:

Fig. 1 is a diagrammatic sectional elevation of a set of casting boxes showing the 45 automatic water circulating system.

Fig. 2 is a diagrammatic sectional elevation of a single casting box and its automatic water circulating system.

Fig. 3 is a diagrammatic sectional elevation.

Fig. 4 is a top plan view of one of the casting boxes.

Fig. 5 is a diagrammatic sectional elevation of the invention applied to a semi-cylindrical plate casting box.

As shown in Figs. 1 to 4 of the drawings, the box comprises a base 7 to which are secured side frames 5 upon which is mounted a drag 1 provided with a semi-cylindrical recess in its front face to receive the core 2 when the latter is in casting position. To the drag 1 is hinged a cope 1^a which can swing to and from the drag, and has a semi-cylindrical recess in its inner face so that when the box is closed, as indicated in Fig. 4, the opposed recesses in the drag and cope form a true cylindric chamber.

The core 2 is mounted on trunnions as usual journaled in the side frames 5, so that said core can be moved to a position axially 75 of the said chamber, (Figs. 1, 2 and 4) when a plate is to be cast; or can be tilted outwardly when the box is opened as indicated in Fig. 3.

In such boxes it is desirable to cool the 80 core, or part with which the molten metal directly contacts, during the casting operations, and therefore (in the box shown in Figs. 1 to 4 of the drawings) the core is made hollow and is provided with internal 85 pipes 11 and 12. One of these pipes 11 communicates at bottom with a passage 3^a leading through one of the trunnions and connected to an elbow 4^a at the outer end of the trunnion. The other pipe 12 communicates with a passage 3 leading through the other trunnion and connected with an elbow 4.

The elbow 4 is connected by a hose section 19^a with a nipple or union 8^a attached 95 to one of the side frames 5, and this union 8^a is connected with a return pipe in any suitable manner. The elbow 4^a is connected by a hose section 19 with a nipple or union 8 attached to the opposite frame 5, and which 100 in turn is connected to a supply pipe in any suitable manner.

The parts thus far described are substantially the same as those shown in my application No. 866,295 aforesaid, and are not 105 specifically claimed herein.

The object of the present invention is to automatically circulate water or other cooling medium through the parts of the box with which the molten metal directly contacts during the casting operation, and for this purpose the inlet nipple 8 is connected by piping 14^b to a pipe 14 leading to the lower end of a reservoir or tank 13 mounted on suitable supports, (not shown) at any desired elevation above the top of the casting box when the latter is in operative position. The outlet nipple 8^a is also connected by piping 15^b to a pipe 15 leading into the tank 13 at a point above the normal water line therein, which is indicated at 18 in Fig. 1. A water gage 17 attached to the tank enables the proper level of water therein to be determined. The tank has a vent pipe 16. Water or other suitable cooling medium can be introduced into the tank 13, as required, through a valved supply pipe 14^d and can be drained from the apparatus when desired by means of a valved drain pipe 15^d. Any suitable cooling fluid might be used instead 25 of water.

It will be seen that normally all portions of the pipes 14 and 15 (below the water line 18) also connections 19, 19^a, passages 3, 3^a, and pipes 11 and 12, and the interior of the core 2, will be normally filled with the cooling medium by gravity.

The construction of the box and arrangement of parts shown in Figs. 2 and 3 are, in general, like those already described. The tank may be located at any desired point and pipes 14 and 15 may be connected directly to nipples 8 and 8^a as shown.

In Fig. 5 a semi-cylindric plate casting box, such as shown in my Patent No. 40 853,752, is represented. In this construction the drag C is hollow and the cope D can be moved to and from the drag in the usual manner. The pipes 11^a and 12^a are arranged within the drag, and pipe 11^a connects at bottom with a pipe 14^a leading to the pipe 14; and the pipe 12^a connects at bottom with a pipe 15^a leading to pipe 15.

Referring to Figs. 1 to 4, when the box is ready for casting a plate, the core 2 is 50 in a vertical position, and the core and all the piping below the water line 18 is filled with water or cooling medium. If the water in the core becomes heated above the boiling point during plate casting operations the steam collects above the pipes 11 and 12, and the pressure of the steam thus formed will tend to expel the water from the pipes 11, 12 back through pipes 14, 15 and intermediate passages into the tank, and the 55 balance of pressure between pipes 15 and 14 is disturbed, and pipe 14 being filled with cooler water from the reservoir 13, and the mixture of steam and water in pipe 15 being lighter than the column of water in

pipe 14, gravity produces a circulation of 65 cooling medium through the box and pipes in the direction indicated by the arrows in Fig. 1. This circulation of water or cooling medium is constant, or nearly constant, and prevents too sudden cooling of the core by 70 the stereotyper carelessly turning on too much cold water, and it also prevents overheating of the core, because the circulation is automatically produced and maintained. The circulation of cooling medium would be 75 produced in like manner in the construction shown in Fig. 5, and need not be specifically described.

In the tubular plate casting boxes shown in Figs. 1 to 4, the core must be tilted to 80 remove the cast plates, and when the core is lowered to remove a plate the heated water, which is at the top of the core, shifts and mixes with the water at the lower end of the core, or near the trunnions, thus 85 creating greater uniformity in the temperature of water in the box. This mixing of the water by tilting the core facilitates and augments the desired circulation of cooling 90 medium.

An advantage of this apparatus is that the box while in use can be maintained at a temperature of about 200 to 250 degrees, which is desirable when casting plates as at such a temperature the plates will not stick. 95 If cold water is allowed to pass suddenly and irregularly into the box the temperature of the box is not uniform and the plates are chilled unequally while being cast; and if the box is not properly cooled it will become so heated that the stereotype metal will 100 adhere to the core or drag, practically becoming soldered thereto. Heretofore considerable trouble has been caused through the boxes not being kept at the proper temperature, but such troubles will be entirely 105 eliminated with boxes equipped with my invention, and plates can be cast therein as fast as the operators can manipulate them, for no matter how rapidly the plates are 110 cast the boxes will not become overheated.

What is claimed is:

1. The combination of a casting box, a tank, and pipe connections extending respectively from lower and upper points in said tank and to two points on substantially the same level in the casting box.
2. The combination of a casting box, having a core, a tank, and pipe connections extending respectively from lower and upper points in said tank and to two points on substantially the same level in the core.
3. The combination of a casting box having a hollow member, a pair of parallel vertically disposed fluid conduits in said member communicating with the interior thereof at their upper ends and at substantially the same level, a tank and connections

whereby cooling fluid is supplied from said tank to the hollow member.

4. In a stereotype casting apparatus the combination with a hollow tilttable member, and conduits within said member communicating with the top part thereof at substantially the same level, of a tank exterior to the member, and connections between said tank and the conduits in the said member

for maintaining supply of cooling fluid is from the tank to said tilttable member.

In testimony that I claim the foregoing as my own, I affix my signature in presence of two witnesses.

HENRY F. BECHMAN.

Witnesses:

IRVING K. STONE,

CHARLES A. GRAMES.
